AIR-LIFT SYSTEM.

1,385,706.

Specification of Letters Patent. Patented July 26, 1921.

Application filed October 7, 1916. Serial No. 124,400.

To all whom it may concern:

Be it known that I, JOHN OLIPHANT, a citizen of the United States, residing at Chicago, in the county of Cook and State of Illinois, have invented certain new and useful Improvements in Air-Lift Systems, of which the following is a full, clear, and exact specification.

My invention relates to air-lift systems. 10 It has for its object to provide an improved air-lift system whereby a constant flow of fluid may be maintained and whereby the available back pressure for delivering to the line the fluid pumped may be 15 readily and conveniently adjusted from the exterior of the booster. A more specific object of my invention is to provide an improved booster adapted to use in such a system, the said booster being provided with 20 improved means for preventing surging and insuring a constant fluid flow, and improved means for adjusting the back pressure exerted on the fluid therein, as well as improved means for removing the several parts 25 inclosed within the booster casing.

In the accompanying drawings, I have for purposes of illustration shown one embodiment which my invention may assume in practice.

30 In these drawings,—

Figure 1 is a diagrammatic view showing a system embodying my invention.

Fig. 2 is a plan view of the booster.

Fig. 3 is a sectional view of the booster 35 taken on line 3—3 of Fig. 2, with parts omitted.

Fig. 4 is a partial sectional view of the booster taken on line 4—4 of Fig. 2.

In the illustrative construction shown, a 40 compressor 1 of any suitable design has its discharge connected through a pipe 2 to a receiver 3, and this receiver is in turn connected through a pipe 4 with the down-pipe 5 of the air-lift mechanism. This pipe 5 extends into the well 6 and delivers air 45 under pressure to the usual foot-piece 7 in such a manner that a mixture of air and water or other fluid is forced up through the pipe 8 into the booster 9, by which the air is 50 then separated from the water or other fluid and the latter expelled downward and outward through the line 10.

As shown, the mixture rising through the 55 pipe 8 enters the booster 9 through an up- standing sleeve 11 which communicates with

the pipe 8 and has a lower flange 12 thereon by which this sleeve is removably attached to the bottom of the booster through suitable screws 13. As illustrated, a clamping ring 14, preferably threaded at 15 to receive the upper end of the pipe 8, is also preferably attached to the flange 12 by suitable screws 16. As the mixture of air and water or other fluid passes out of the sleeve 11, it strikes an umbrella top 17, preferably of the flanged and conical type shown, suitably attached to the top of the booster 9 and is deflected thereby, the water passing downward into the bottom of the booster casing at one side of a transversely disposed baffle- 70 plate 18 which, as shown, extends from a point near the top of the booster 9 to a point a greater distance above the bottom thereof. The water then passes under this baffle-plate 18 and up on the other side of the same 75 through suitable vertically disposed slots 19 in an upstanding sleeve 20. As shown, this sleeve also preferably has a lower flange 21 thereon which is fixed to the bottom of the casing 9 by screws 22 and, as in the case of 80 the flange 12, also carries by screws 23 a ring 24, threaded at 25 to receive the end of the pipe 10. Carried upon the upper end of this sleeve 20 is also another sleeve 26 of greater diameter which extends almost to the top of 85 the booster casing. As shown, this sleeve 26 rests on radially disposed lugs 27 on the lower end of the sleeve 20 and is secured to that sleeve by screws 29 received in radially disposed lugs 28 on the upper end of the 90 latter.

Coöperating with the mechanism just described is improved adjustable means for maintaining a constant pressure of the air trapped between the surface of the water 95 in the booster tank and the top thereof. As shown, these means include a hollow, laterally apertured valve 30 herein shown to be disposed on the opposite side of the baffle 18 from the sleeve 11 and movable in 100 a valve casing 31, which is, in turn, carried on a plate 32 disposed over a hand hole 33 in the top of the booster casing and removably attached to the latter by bolts 34. This valve 30 is controlled by a hollow diving bell float 35, open at its bottom, which is disposed in the booster casing on the same 105 side of the baffle-plate 18 as the sleeve 20, and is vertically adjustable on a vertically disposed threaded rod 36, being held in any 110

desired position on said rod by jam nuts 37. As shown, this rod 36 is itself seated in a suitable socket 38 and connected to the valve 30 at its upper end, so that the float and valve 5 will normally assume the position shown in Fig. 4, wherein it will be noted that the valve is open and that the space at the top of the booster is connected with a vent pipe 39 which may either exhaust to the atmosphere or be connected to the inlet of the compressor, as desired. Obviously, when the water level in the booster 9 rises to a predetermined point, the float 35 will be raised from the position shown in Fig. 4 to 10 close the outlet through the valve 30 and trap the air at the top of the booster in such a manner as to produce a back pressure acting upon the surface of the water in the booster and impelling the same out through 15 the line 10. Further, so long as the float 35 is set in a predetermined position on the rod 36, it will maintain this pressure, opening the valve to permit excess pressure to escape whenever the water level in the booster 20 is lowered to too great an amount by said excess pressure.

In the operation of the device described, it is apparent that the air and water entering through the pipe 8 will be separated by 30 the action of the umbrella top 17 and the baffle-plate 18 in such a manner that the water will flow down and under the baffle-plate 18, and over to the outlet sleeve 20 to the line, while the air will be trapped above 35 the surface of the water in such a manner as to enable it to exert a pressure thereon and thereby impel the water through the line, surging in the booster being prevented by the baffle-plate, and other interruptions of 40 flow, such as those arising from a variation in level of the water, being prevented by the sleeves 11, 20 and 26. Here it will also be noted that through the provision of the baffle-plate 18, which is disposed between 45 the sleeve 11 and the float 35, the valve 30 is protected from such jamming or other interference with its operation as would otherwise result from the water surging against the float. As brought out above, it will also 50 be noted that through the action of the valve 30, a constant flow of fluid will be maintained and that, through the provision of the adjustable float 35, the water level and back pressure available may be regulated as 55 desired by simply removing the hand hole cover 32, withdrawing the float 35, and adjusting the same longitudinally of its rod 36.

It should also be noted that in my improved construction, the sleeve 11 may be 60 bodily withdrawn from the booster whenever desired and that the sleeves 20 and 26 may also be bodily withdrawn from the booster. Attention is also directed to the fact that, if desired, the excess pressure relieved by the valve 30 may be conducted 65

through the vent pipe 39 to the inlet of the compressor in such a manner as to economize in the operation of the system. It will also be obvious that, if desired, suitable pressure gages 40 and 41 may be inserted in 70 the connection between the down-pipe 5 and the receiver 3 and on the booster 9, respectively, while suitable regulating valves 42 and 43 may, if desired, be inserted between the booster 9 and the compressor inlet, and between the receiver and the down-pipe 5, respectively, a suitable regulating valve 44 75 also preferably being inserted as shown between the booster and the gage 41. In view of the relatively rapid but small fluctuations 80 in pressure in the booster, it is found desirable to choke the connection to the gage so as to steady the needle and enable the making of an accurate reading. Also the presence of this valve permits the closing of this connection and the removal of the gage for use upon another booster if desired, when, for 85 reasons of economy, it may be thought desirable not to have a separate gage for each booster.

While I have in this application specifically described one embodiment which my invention may assume in practice, it is of course to be understood that the same may be modified without departing from its 95 spirit, and that I intend to cover all such modifications within the scope of the appended claims.

What I claim as new and desire to secure by Letters Patent is:

1. In an air-lift booster, a booster casing, inlet and discharge pipes therein, a vertically movable rod therein, guiding means therefor in said casing, a valve casing, a vent-valve on said rod guided by said valve casing, and a single float carried on said rod.

2. In an air-lift booster, a booster casing, inlet and discharge pipes therein, a vertically movable rod therein, guiding means therefor in said casing, a valve casing, a vent-valve on said rod guided by said valve casing, and a single valve operating means consisting of a diving bell float carried on said rod.

3. In an air lift booster, a booster casing, 115 inlet and discharge pipes communicating therewith, a vent valve for said casing, means disposed in said casing and responsive to conditions therein for controlling said vent valve, and means for preventing 120 lateral surging in said casing comprising a baffle plate disposed therein between said first mentioned means and said inlet pipe and having its lower edge extending below the minimum liquid level therein.

4. In an air lift booster, a booster casing, inlet and discharge pipes communicating therewith, a vent valve for said casing, means disposed in said casing and responsive to liquid variations therein for controlling 130

5 said vent valve, and means for preventing lateral surging in said casing comprising a baffle plate disposed therein between said first mentioned means and said inlet pipe and having its lower edge extending materially below the normal liquid level therein.

10 5. In an air lift booster, a booster casing, inlet and discharge pipes communicating therewith, a vent valve for said casing, means disposed in said casing and responsive to conditions therein for controlling said vent valve, and means for preventing lateral surging in said casing comprising a baffle 70 plate disposed therein between said first mentioned means and said inlet pipe and having its lower edge extending below the minimum liquid level therein and its upper edge terminating short of the top of said 75 booster casing.

15 6. In an air lift booster, a booster casing, inlet and discharge pipes communicating therewith, a vent valve for said casing, means in said casing for controlling said 80 vent valve comprising a float operatively connected to said vent valve, and means for preventing lateral surging in said casing comprising a baffle plate disposed in said casing between said inlet and said float and 85 said discharge pipe, said baffle having its lower edge extending below the minimum liquid level in said booster casing.

20 7. In an air lift booster, a booster casing, an umbrella top therein, an inlet member 90 leading to a point adjacent said umbrella top, an outlet member having openings therein, a coöperating sleeve of greater diameter than said outlet member inclosing the openings therein and having open ends 95 spaced from the ends of said booster casing, and a baffle plate disposed transversely between said inlet and outlet members and extending below the minimum liquid level in said booster casing.

25 8. In an air lift booster, in combination, a booster casing, inlet and discharge connections therefor, a vent valve casing carried by said booster casing, a ported vent valve reciprocable in said valve casing and 100 guided thereby, and a float connected to said valve and disposed within said booster casing.

30 9. In an air-lift booster, a booster casing, inlet and discharge pipes therein, a vent-valve casing disposed on said booster casing, a hollow vent-valve reciprocable in said valve casing and having a lateral port therein, and a float connected to said valve and disposed within said booster casing.

35 10. In an air lift booster, in combination, a booster casing, inlet and discharge connections therefor, a vent valve guided for vertical reciprocation in said casing and having a rod, a float on said rod, and means 105 between said inlet connection and said float

for inhibiting lateral surging in said casing and jamming of said valve.

11. In an air lift booster, in combination, a booster casing, inlet and discharge connections therefor, a vent valve for said casing, a valve float, means for guiding said vent valve and float in said casing, and means for adjusting one of said last mentioned elements relative to the other to control the operation of the other. 75

12. In an air lift booster, in combination, a booster casing, inlet and discharge connections therefor, a vent valve for said casing, a valve float, a valve rod connecting the same, and means for adjusting said float longitudinally thereof relative to said valve to vary the action of the latter. 80

13. In an air lift booster, in combination, a booster casing, inlet and discharge connections therefor, a vent valve carried by 85 said booster casing, and a single diving bell float carried in said casing and operatively connected to said valve and coöperating with the latter to maintain a substantially constant liquid flow from said casing. 90

14. In an air-lift booster, a booster casing having a top and an aperture therein, a valve casing removably disposed over said aperture, a vent-valve movable in said valve casing, coöperating means within said 95 booster casing for guiding said valve, and a float movable with said valve and removable through said aperture.

15. In an air-lift booster, a booster casing, a valve casing thereon, a vent-valve movable 100 in said valve casing, coöperating valve guiding means in said casing, a single float movable with said valve to maintain a substantially constant pressure in said casing, and means for adjusting the time of operation of 105 said valve.

16. In an air-lift booster, a booster casing having a top and an aperture therein, an apertured plate disposed over said aperture, a valve casing carried by said plate, a valve 110 movable in said valve casing, a rod connected to said valve and disposed through said apertures, and a float carried by said rod.

17. In an air-lift booster, a booster casing, a discharge pipe extending into the same, a coöperating sleeve disposed around said discharge pipe and secured thereto, and means whereby said discharge pipe and sleeve may be bodily inserted in said booster 115 casing. 120

18. In an air-lift booster, a booster casing, a sleeve extending into the same and having a flange on its lower end, means for attaching said flange to said booster casing, a pipe communicating with said sleeve, a threaded clamping ring surrounding said pipe, and means for securing said clamping ring to the flange on said sleeve. 125

19. In an air-lift booster, a booster casing, 130

a sleeve extending into the same and having a plurality of fluid openings therein, and a coöperating coaxially disposed sleeve of larger diameter open at the top and inclosing said openings, said last mentioned sleeve extending from a point above the bottom of said casing to a point slightly removed from the top thereof.

20. In an air-lift booster, a booster casing, a sleeve extending into the same and having a plurality of fluid openings therein, a coöperating sleeve of larger diameter fixed to said sleeve and inclosing said openings, said last mentioned sleeve extending from a point above the bottom of said casing to a point slightly removed from the top thereof, and means whereby said sleeves may be bodily inserted in said booster casing.

21. In an air-lift booster, a booster casing, inlet and discharge pipes therein, said booster being adapted to produce a continuous liquid flow, a vertically movable rod therein, guiding means therefor in said cas-

ing, a valve casing, a vent-valve on said rod guided by said valve casing, and a single float carried on said rod.

22. In an air-lift booster, a booster casing, inlet and discharge pipes therein, said booster being adapted to produce a continuous liquid flow, a vertically movable rod therein, guiding means therefor in said casing, a valve casing, a vent-valve on said rod guided by said valve casing, and a diving bell float carried on said rod.

23. In an air-lift booster adapted to produce a continuous liquid flow, a booster casing, a valve casing thereon, a vent-valve movable in said valve casing, coöperating valve guiding means in said casing, a float movable with said valve to maintain a substantially constant pressure in said casing, and means for adjusting the time of operation of said valve.

In testimony whereof I affix my signature.

JOHN OLIPHANT.
